UNITED STATES PATENT OFFICE

WILLIAM F. KELLEY, OF CHICAGO, AND ORIE L. WOOD, OF CLINTON, ILLINOIS.

LOCOMOTIVE-CURTAIN.

1,131,525.

Specification of Letters Patent.

Patented Mar. 9, 1915.

Application filed December 4, 1914. Serial No. 875,507.

To all whom it may concern:

Be it known that we, WILLIAM F. KELLEY and ORIE L. Wood, citizens of the United States, residing at Chicago and Clinton, respectively, in the counties of Cook and DeWitt, State of Illinois, have invented a new and useful Locomotive-Curtain, of which the following is a specification.

This invention relates to a curtain for use in connection with locomotives, one of its objects being to provide means whereby the space between the cab of a locomotive and the tender will be closed at the sides to protect the occupants of the cab from the weather, the said shield being so constructed as to be readily pushed aside by a person entering or leaving the cab.

A further object is to provide a shield or curtain which can be applied readily to the cab of a locomotive and which can be easily pulled to one side where it will be out of the way but which, when closed, will remain in such position without danger of working to an open position.

25 A further object is to provide a shield or curtain, the lower end of which extends below the floor of the cab so that there is no danger of the curtain flapping inwardly where it will interfere with the fireman in passing coal.

30 Another object is to provide a shield or curtain which will not blow inwardly and which can be pushed aside readily even though covered with sleet, to permit the engineer or fireman to enter or leave the cab.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 45 within the scope of what is claimed, without departing from the spirit of the invention.

In the accompanying drawings the preferred form of the invention has been shown.

50 In said drawings: Figure 1 is a side elevation of a portion of a locomotive and tender and showing the curtain in position to close the space therebetween. Fig. 2 is a section on line A—B of Fig. 1. Fig. 3 is a view partly in side elevation and partly in section of the upper portion of the shield

or curtain and its supporting means, parts being broken away. Fig. 4 is an enlarged section on line C—D Fig. 3. Fig. 5 is an enlarged section on line E—F Fig. 3. Fig. 6 is an enlarged side elevation of a portion of the upper end of the shield or curtain. Fig. 7 is a section on line G—H Fig. 6.

Referring to the figures by characters of reference L designates a portion of a locomotive cab having the usual rearwardly extending roof R designed to overhang the front portion of the tender T. Steps such as indicated at S depend from the deck or floor of the cab and the usual hand rails X are provided upon the cab and tender where they can be grasped readily by a person ascending or descending the steps.

The curtain or shield constituting the present invention is hung from a substantially horizontal rod 1, one end of which is seated in an opening 2 in the wall of the cab while the other end is offset downwardly to form a seat or depression 3 from which projects an upwardly extending arm 4 having a finger 5 parallel with the rod 1. This finger extends through the rear portion of the roof structure to which it may be secured in any suitable manner. Thus it will be seen that by means of two nuts 6 engaging the threaded end 7 of the finger 5, the rod 1 can be held securely to the cab structure. This rod extends close to the upper portion of the side wall of the tender as will be seen by referring to Fig. 1.

The curtain or shield used in connection with the rod can be made of any suitable material, such as heavy canvas, indicated at 8, this sheet of flexible material being so proportioned as to completely close the space between the cab and the tender and to extend from a point close to the roof R downwardly to a point below the rearwardly projecting portion of the deck or floor of the cab. In order to prevent the fabric from buckling, cleats 9, preferably of half round strips of wood, are riveted or otherwise secured upon opposed faces of the fabric, these cleats extending throughout the length of the fabric. Each of the cleats is provided, at its upper end, with a loop 10 the ends of which are extended transversely through the cleats and clenched as shown particularly in Fig. 7. These loops slidably engage the rod 1 and that loop 10 which is attached to the cleats most remote from the cab of the locomotive is

designed, when the curtain or shield is in use, to rest within the seat or depression 3 as shown in Fig. 3. That edge of the fabric 8 nearest the wall of the cab is held to said 5 wall by a cleat or strip 11 which clamps the marginal portion of the fabric as shown in Fig. 5.

As the shield or curtain extends slightly below the side of the deck of the cab, it will be seen that pressure of wind against the outer face of the curtain will not result in the curtain being blown inwardly where it will interfere with the fireman passing coal. Instead the cleats secured upon the curtain will stiffen said curtain.

As the curtain is made of a flexible material, it can be readily pushed or pulled aside and outwardly thus to permit a person to pass out of or into the cab without necessitating the collapse or folding of the curtain. This is due to the fact that said curtain is free to swing outwardly about the rod 1. When desired, the entire curtain can be collapsed or folded simply by lifting 20 the rearmost cleat 9 to disengage its loop 10 from the seat or depression 3, whereupon all 25 of the loops 10 can be slid along rod 1 toward the cab wall.

From the foregoing it will be apparent 30 that a very simple, durable and efficient curtain is provided which completely closes the space between the cab and the tender so as thus to afford full protection from the weather, the operation of the curtain 35 being such that it becomes no detriment or hazard to the engine crew in case of accident or in operating the engine.

While the structure herein described is especially designed for use in connection 40 with locomotive cabs, it is to be understood that the same can be used wherever it is desired to provide a flexible closure for a side opening in a car of any type, pilot house on a boat or the like.

45 What is claimed is:—

1. The combination with a locomotive cab or the like of a curtain, including a support having a seat at one end, a flexible element, spaced stiffening means extending 50 from the top to the bottom of said element and lapping the floor of the cab, and a slidable connection between each of the stiffening means and the support, one of said connections being adapted to rest 55 within the seat to hold the flexible element extended.

2. The combination with a locomotive cab or the like, of a curtain including a substantially horizontal supporting element 60 having a seat at one end, a flexible element, means for securing one side edge thereof to the locomotive structure, spaced stiffening means secured to the flexible element and extending from the top to the bottom thereof and lapping the floor of the cab, and 65

slidable connections between the upper ends of said stiffening means and the supporting element, one of said connections being adapted to engage the seat to hold the flexible element extended.

3. The combination with a locomotive cab or the like, of a curtain including a substantially horizontal supporting rod having a seat at one end, means extending from said end for engaging the locomotive structure to support the rod in active position, a flexible element, means for securing one side edge of said flexible element to the locomotive structure, stiffening elements secured to the flexible element and extending 70 from the top to the bottom thereof, said stiffening elements being spaced apart and lapping the floor of the cab, and loops carried by said elements and slidably engaging the rod, that loop remote from the fastened side of the flexible element being adapted to engage the seat to hold said flexible element extended.

4. The combination with the cab of a locomotive or the like, of a supporting element secured to the roof thereof and having a seat adjacent one end, a curtain having its lower end extending below one side of the deck of the cab, spaced stiffening means secured to the curtain and extending from 90 the top to the bottom thereof, and slidable connections between the upper ends of said stiffening means and the supporting means, one of said connections being adapted to engage the seat to hold the curtain extended, said stiffening means coöperating 95 with the side of the deck to prevent the curtain from buckling inwardly.

5. The combination with the cab of a locomotive or the like, of a supporting element secured to the roof thereof and having a seat adjacent one end, a curtain having its lower end extending below one side of the deck of the cab, spaced stiffening means secured to the curtain and extending from 100 the top to the bottom thereof, slidable connections between the upper ends of said stiffening means and the supporting means, one of said connections being adapted to engage the seat to hold the curtain extended, said stiffening means coöperating 105 with the side of the deck to prevent the curtain from buckling inwardly, and a connection between one side edge of the curtain and the cab structure, said curtain being adapted 110 to swing outwardly about its supporting means to permit the entrance or exit of a person to or from the cab respectively.

6. The combination with a locomotive cab or the like having a side opening, of a curtain including a support secured to the cab, a flexible element, means secured to said element for slidably engaging the support, and spaced stiffening means extending from the top to the bottom of the flexible element and 120

adapted to lap and extend below the side of the floor of the cab.

7. The combination with a locomotive cab or the like having a side opening, of a curtain including a support secured to the cab, a flexible element, means secured to said element for slidably engaging the support, spaced stiffening means extending from the top to the bottom of the flexible element and 10 adapted to lap and extend below the side of the floor of the cab, and means upon the

support and coöperating with one of said support engaging means for holding the flexible element extended.

In testimony that we claim the foregoing 15 as our own, we have hereto affixed our signatures in the presence of two witnesses.

WILLIAM F. KELLEY.
ORIE L. WOOD.
